ATTORNEY.

UNITED STATES PATENT OFFICE.

EDWIN PUGSLEY, OF NEW HAVEN, CONNECTICUT, ASSIGNOR TO THE WINCHESTER REPEATING ARMS COMPANY, A CORPORATION OF CONNECTICUT.

BATTERY CANDLE.

1,421,561.

Specification of Letters Patent.

Patented July 4, 1922.

Application filed November 3, 1921. Serial No. 512,415.

To all whom it may concern:

Be it known that I, EDWIN PUGSLEY, a citizen of the United States, residing at New Haven, in the county of New Haven, State 5 of Connecticut, have invented certain new and useful Improvements in Battery Candles; and I do hereby declare the following to be a full, clear, and exact description of the invention, such as will enable others 10 skilled in the art to which it appertains to make and use the same.

The present invention relates to a battery hand lamp having a size and form comparable to that of an ordinary tallow candle 15 and adapted for use in place of such burning candles for the illumination of banquet tables, Christmas trees and the like, and for use as a night light by children and in the sick room.

20 In the preferred embodiment of the present invention a plurality of dry cells placed end to end are housed in a tubular casing of paper, preferably rolled and pasted in much the same way that a shot gun shell is made, 25 the lower end of this paper casing being closed with a wad or disc held in by a crimping of the lower end of the tube. Other details and objects will become clear from the following description taken in conjunction 30 with the accompanying drawings, wherein—

Fig. 1 is a sectional elevation of a battery candle constructed in accordance with the present invention;

Fig. 2 is a section of the tubular casing 35 ready for the introduction of the battery;

Fig. 3 shows a plurality of dry cells arranged within a pasteboard carton;

Fig. 4 is a side view of the flat conductive strip used for connecting the lowermost dry 40 cell with one terminal of the battery.

In the embodiment illustrated in the drawing, the plurality of dry cells 1 and 2 are arranged within an insulating carton 3 of cardboard or the like in conformity with 45 usual practice. A conductor 4 in the form of a flat metal strip lies along the side of this carton and has its lower end 5 bent sharply upward and positioned on the inside of the carton to lie against the zinc can of 50 the lower dry cell 1 and thereby establish electrical connection therewith. The upper

end of this conductor is bent inward above the upper dry cell to serve as a yielding contact finger 6.

The tubular casing 7 into which the parts 55 above described are to be inserted, is preferably made of waterproofed paper rolled and pasted on a shotgun shell machine, and of a size to closely envelop the carton of dry cells and the conductive strip 4. At its front end 60 this tubular casing is flared at 8 by a crimping operation and has its upper edge doubled back in a crimp at 9. After the conductive strip 4 has been slipped into position against the lowermost dry cell, and the structure thus formed has been shoved forward into tube 7, the bottom of that tube is provided with a closure 10 in the form of a disc or wad of felt or cardboard, such as is used in shotgun shells, this being pressed inward 65 and held snugly against the bottom of the lower dry cell by a crimp 11 in the lower end of the tubular casing.

The incandescent bulb 12 of the battery candle can be screwed into the crimped upper end of the tubular casing and will form its own threads in the inner fold of the paper. The inner terminal of the lamp rests on the upper terminal 13 of the battery, and the outer threaded terminal of the lamp is 70 in electrical connection with the yielding finger 6 of the conductive strip. To extinguish the candle the lamp bulb 12 is unscrewed enough to open the circuit at terminal 13.

85 With the construction above described, the tubular casing may be white or may be colored and the contracted upper end in conjunction with the bulb of the lamp gives to the structure as a whole a shape simulating 90 that of an ordinary tallow candle. The circuit through the lamp can be conveniently controlled by simply turning the lamp bulb in its socket, as above described. The structure is light in weight, cheap to build, is 95 easily packed for shipment and can be safely used by children or where fire hazard does not permit the use of an open flame.

There is no provision for renewing the battery, as it is intended that the battery 100 and its casing shall be thrown away after it is exhausted, only the lamp bulb being re-

tained by the user. Ordinarily the bulb will outlast the batteries and can be preserved and used in new battery candles.

Changes in details of structure and assembly may be made without departing from the spirit of my invention as defined by the appended claims.

1. In a battery hand lamp, a tubular casing of paper having its front end turned back in a crimp into which an incandescent lamp bulb may be threaded, substantially as described.

10 2. In a battery candle, a tubular casing of wrapped and pasted paper having its upper 15 flaring end turned back in a crimp into which a lamp bulb can be threaded, substantially as described.

3. In a battery candle, the combination of 20 a tubular casing of wrapped and pasted paper the upper flaring end of said casing being crimped inward to serve as a socket for a lamp bulb, a battery in said casing electrically connected with said lamp and a closure for the lower end of said casing held by a 25 crimp at the lower end thereof.

4. In a battery candle, the combination of 30 a plurality of dry cells, an insulating wrapping therefor, a conductor lying along the side of said cells and electrically connected with the lowermost and having its upper end 35 positioned to serve as a contact, a tubular casing of paper closely enveloping said dry cells and said conductor, and having its upper end crimped, a lamp threaded into said crimp and adapted to contact with the adjacent dry cell, and a closure crimped into the lower end of said casing.

5. In a battery candle, the combination of 40 a plurality of dry cells, an insulating carton therefor, a conductive strip lying along the side of said carton and insulated thereby, said strip having its lower end electrically connected with the zinc can of the lower dry cell and having its upper end positioned to

serve as a contact finger, a tubular casing of 45 rolled and pasted paper closely enveloping said dry cells and said strip and having its upper flaring end doubled back in a crimp, and a lamp threaded into said crimp and adapted to contact with the adjacent dry cell 50 and said contact finger.

6. In a battery candle, the combination of a plurality of dry cells, an insulating carton therefor, a conductive strip lying along the side of said carton and insulated thereby, 55 said strip having its lower end electrically connected with the zinc can of the lower dry cell and having its upper end positioned to serve as a contact finger, a tubular casing of 60 rolled and pasted paper closely enveloping said dry cells and said strip and having its upper flared end doubled back in a crimp, a lamp threaded into said tubular casing of 65

7. In a battery candle, the combination of a plurality of dry cells, an insulating carton therefor, a flat conductive strip lying along the side of said carton and insulated 70 thereby, the said strip having its lower bent end positioned on the inside of said carton and lying against the zinc can of the lower dry cell to establish electrical connection therewith and having its upper end bent inwardly above the upper dry cell to serve as a yielding contact finger, a tubular casing of 75 rolled and pasted waterproofed paper closely enveloping said dry cells and said strip and having its upper flared end doubled 80 back in a crimp, a lamp threaded into said crimp and adapted to contact with the adjacent dry cell and said yielding contact finger, and an insulating disc held snugly against the bottom of the lower dry cell by a crimp 85 at the lower end of said tubular casing.

In testimony whereof I affix my signature.
EDWIN PUGSLEY.
